(57) **CLAIM**

What is claimed is the ornamental design for a “Bin,” as shown and described.

DESCRIPTION

FIG. 1 is a perspective view showing a new design for a bin; FIG. 2 is a top plan view of the bin of FIG. 1;

FIG. 3 is a right side view of the bin of FIG. 1, the left side view being a mirror image thereof;

FIG. 4 is a front view of the bin of FIG. 1;

FIG. 5 is a rear view of the bin of FIG. 1; and,

FIG. 6 is a bottom plan view of the bin of FIG. 1.

The broken lines are for illustrative purposes only and form no part of the claimed design.
